UNITED STATES PATENT OFFICE

THEODOR BERGMANN, OF GAGGENAU, BADEN, ASSIGNOR TO GEBR STOLL-WERCK, OF COLOGNE-ON-THE-RHINE, GERMANY.

SIPHON-BOTTLE.

SPECIFICATION forming part of Letters Patent No. 320,751, dated June 23, 1885.

Application filed March 31, 1885. (No model.)

To all whom it may concern:

Be it known that I, THEODOR BERGMANN, of the city of Gaggenau, in the Grand Duchy of Baden and German Empire, have invented 5 a certain new and useful Improvement in Siphons, of which the following is a specification, reference being had to the accompanying drawings, and to the letters of reference marked thereon.

10 This invention relates to siphon-bottles for aerated or gaseous liquids; and it consists in the novel combination of devices hereinafter described and claimed, reference being made to the accompanying drawings, in which—

15 Figure 1 is a vertical transverse section of the improved apparatus, the bottle being closed. Fig. 2 is a front view of the apparatus open, and Fig. 3 a similar view of the apparatus closed. Fig. 4 is a top view of the 20 apparatus, and Fig. 5 is a horizontal transverse section of the same on the line A B, Fig. 2.

Like letters of reference indicate similar parts throughout the drawings.

25 a indicates a bottle having a centrally-perforated plate, b, placed upon a shoulder formed on the upper inner flange of the said bottle. The plate has fixed to its under side a pipe or tube, c, and to its upper side a funnel-shaped 30 pipe, d, communicating with the pipe c through the said central opening in the plate b, or forming a continuation of the said pipe c. The upper flange of the said funnel-shaped pipe is covered with an annular piece of india-rubber or other suitable packing material.

35 e is the bell-shaped siphon-head, pivoted at g to the ring f around the neck of the bottle a, the interior part of the head e being of such shape that when closed it will bear or 40 press upon the upper india-rubber-covered flange of the funnel d, and thus form a hermetically-closed joint between the upper part of the head e and the pipe c.

Instead of connecting the head to the bottle 45 as hereinbefore described, it may be attached thereto in any other suitable manner. To the said upper part of the head e are applied, in the usual manner, well known in the construction of siphon-bottles, the outflow-pipe

h, the presser-handle i, and the conical valve 50 k, with the rod l and spring m. The lower rim of the head e is provided with a thick ring, n, of india-rubber, in order to cause the said head to hermetically close upon the bottle proper. The head e and its several 55 parts are locked in position by means of the hooked handle o, pivoted to the ring f, and catching over a suitable projection provided near the lower flange of the head e.

p is a small box or receptacle, open at its 60 top, and arranged upon the pipe c so that it may slide thereon.

The operation of the improved apparatus when it is to be applied for producing aerated drinks is as follows—that is to say, after having pressed down the handle o the head e is thrown back, and a liquid, such as still wine, water, or the like, is poured into the bottle a, so as to fill about three-fourths thereof. The receptacle p is then moved by hand near to 70 the upper end of the pipe c, and filled with the proper amount of some suitable substance for producing carbonic acid—for instance, with such as has been referred to hereinbefore—whereupon the head e is brought down 75 upon its seat and locked in position again, thus establishing the proper and hermetically-sealed connection between the several working parts of the apparatus. The receptacle p, with the said effervescent substances arranged therein, will then be above the level of the liquid within the bottle a, and will remain so until it is desired to prepare and use the aerated drink. The bottle is then turned 80 upside down or shaken, so as to bring the said substances in contact with the liquid, and to cause thereby the aeration of the latter. The pressure of the carbonic acid thus produced will, on pressing the handle i, force the aerated drink from the bottle, all this being well understood and requiring no further description. The pressure exerted by the carbonic acid having emptied the bottle of its contents, the head e is opened, whereupon the bottle 85 may be readily cleaned and replenished, and the operation repeated as described.

It will be seen that with a siphon constructed as herein described there can be no loss

of carbonic acid, the latter being produced only after all parts are hermetically closed and when the drink is desired to be consumed.

Having thus described my invention, what 5 I claim as new, and desire to secure by Letters Patent, is—

1. The combination, with a siphon-bottle having a shouldered mouth, of a siphon-head, *e*, a plate, *b*, seated on the shouldered mouth 10 of the bottle, the tube *c*, fixed to the under side of the plate, and the funnel-shaped pipe *d*, fixed to the upper side of the plate and communicating with the tube through the said plate, substantially as described.

15 2. In a siphon bottle or apparatus for producing aerated drinks, the combination, with the removable head *e*, having an inner flange fitting hermetically upon the pipe *d*, and a lower flange fitting hermetically upon the bot-

tle *a*, of the pipe *d*, the plate *b*, and the pipe 20 *c*, substantially as and for the purpose specified.

3. The combination of the siphon-bottle, the plate *v*, seated at the upper end thereof, the tube *c*, depending from the under side of 25 the plate, the pipe *d*, rising from the upper side of the plate and having a flanged upper end covered with rubber, and the siphon-head *e*, hinged to the bottle and adapted to bear against the flanged end of the pipe, substantially as described.

In testimony whereof I have signed my name to this specification in the presence of two subscribing witnesses.

THEODOR BERGMANN.
